DAVID STUART AND LEWIS BRIDGE, OF PHILADELPHIA, PENNSYLVANIA,
ASSIGNORS TO STUART, PETERSON & CO., OF SAME PLACE.

Letters Patent No. 77,549, dated May 5, 1868.

IMPROVEMENT IN BASE-BURNING STOVES.

The Schedule referred to in these Letters Patent and making part of the same.

TO ALL WHOM IT MAY CONCERN:

Be it known that we, DAVID STUART and LEWIS BRIDGE, of Philadelphia, county of Philadelphia, State of Pennsylvania, have invented an Improved Heating-Stove; and we do hereby declare the following to be a full, clear, and exact description of the same.

Our invention consists of certain improvements in heating-stoves, fully described hereafter, our improvements being such that large volumes of cold air are introduced to the stove at different points, thoroughly distributed and circulated throughout, and heated in the said stove, and rapidly discharged in one volume into a chamber at the top of the stove, from which the heated air may be conveyed to different points.

In order to enable others skilled in the art to make and use our invention, we will now proceed to describe its construction and operation, reference being had to the accompanying drawing, which forms a part of this specification, and in which—

Figure 1, Drawing No. 1, is a front view of our improved stove.

Figure 2, a sectional plan on the line 1-2, fig. 1.

Figure 3, a sectional plan on the line 3-4, fig. 1.

Figure 4, a sectional plan on the line 5-6, fig. 1.

Figure 5, Drawing No. 2, a vertical section on the line 7-8, fig. 1.

Figure 6, a sectional plan on the line 9-10, fig. 5.

Figure 7, a vertical section on the line 11-12, fig. 5.

Figure 8, a perspective view of part of the stove.

A is the bottom-plate of the stove, between which and the plate B, which carries the grate, a, intervenes A is the bottom-plate of the stove, between which and the plate B, which carries the grate, a, intervenes the ash-pit C, bounded laterally by the casing c c' c'', fig. 3, and between the ash-pit and the outer casing D of this part of the stove intervenes the chamber E, to which air is admitted from below through openings e in the bottom upper base-plate B of the stove.

On this plate B rests the fire-pot F, contained within but arranged at a distance from the casing G, which is fitted on the said plate B, this casing G being, in front, carried up to the point n, figs. 1 and 8, but the rear is carried higher up, so as to meet the plate H.

An oval casing, I, rests on the top of the fire-pot, and meets the casing G at the points x x, figs. 2 and 8, so that there is a crescent-shaped air-chamber, K, between the rear of the casing I and the rear of the casing G. This arrangement of plates will be best understood by referring to the perspective sketch, fig. 8.

Into this crescent-shaped air-chamber K passes (through openings i in the plate B) the air which had been admitted into the chamber E.

Air also passes through openings i' into the space or chamber F', fig. 4, between the fire-pot and the casing G, and passes thence directly into the chamber K, where it meets the air which passes from the chamber E, (see figs. 4 and 5.)

The casing I, within which is the fire-chamber, has in front a number of openings, g, to which mica is fitted, and the upper edge of the said casing is secured to the outer edge of a plate, J, to the edge of an opening in which is fitted the lower edge of a casing, L, fig. 5.

The upper edge of the casing G is secured to a plate, H, and to the latter is secured the lower edge of another casing, M, and that of another casing, N.

The two casings L and N form together the crescent-shaped air chamber Q, best observed on reference to fig. 6, the two casings being united at y y, so that there may be, through the opening between these points, a free passage for the products of combustion from the fire-chamber to the space between the casings M and N, the products passing off from this space at the rear of the stove through the exit-opening M'.

The plates H and J are a short distance apart from each other. The space between them, however, is closed

at the back by the casing G meeting the plate H. In front, however, there is an opening, q, figs. 1 and 5, for the admission of external air to the crescent-shaped chamber Q.

The upper edges of the plates M, L, and N are fitted to the plate R, in which is a central opening for the coal-reservoir S, which is suspended from the said plate, and projects downwards to about the middle of the fire-chamber, fig. 3.

Near its lower end this coal-reservoir is made double, and an annular air-chamber, h, formed there, a communication between this chamber and the external air being formed by a pipe, v.

The lower end of the chamber is perforated with small holes, for a purpose explained hereafter.

A hot-air or receiving-chamber, T, which has a perfect communication with the crescent-shaped chamber Q, is formed on the top of the stove, and within this chamber T is the curved conductor U, for conveying the fuel to the reservoir S.

In front of this portion of the stove are sliding doors V, which can be made to open or close the entrance to the conductor, and within the latter are ledges for receiving the detachable cover-plate W, more fully referred to hereafter.

On reference to fig. 7, it will be seen that on the outside and on each side of the chamber T there is a receptacle for containing water, the receptacle 2, which has a close cover, 3, communicating through small openings with the interior of the receiving-chamber T, to which the steam from the water is admitted. The receptacle 4, however, has no such communication with the said chamber T, and has an open-work cover; hence it will be seen that the heated air which passes into the room containing the stove, as well as the heated air which is carried upwards from the chamber T to the rooms above, is purified by the steam passing from the receptacles.

The above-described stove possesses several advantageous features, which may be generalized as follows:

First. The introduction of large volumes of cold air at different points.

Second. The thorough heating of the air thus introduced, by causing it to circulate most advantageously throughout the stove, in contact with the heating-surfaces.

Third. The discharge of a large volume of thoroughly-heated air from the stove at a high velocity.

As to the first of these advantages, it will be seen that air is admitted at three points: first, through openings e in the base-plate A; second, through the openings i i in front of the stove; and, third, through the opening q above the fire-chamber.

As to the second advantage, namely, the proper distribution and circulation of this air within the stove, in contact with the heating-surfaces, it will be seen that the air admitted through the openings i i comes in contact with the heated surface of the fire-pot, passes round the same through the chamber F', where, in an intensely-heated state, it meets and imparts a portion of its heat to the colder air passing upward through the openings e, above referred to.

As every portion of the casings L and N, which enclose the air-chamber Q, fig. 6, is exposed to intense heat, the air admitted to this chamber through the opening q must have a correspondingly-intense heat imparted to it, and this heated air is met by that passing from below, until the whole is delivered, at a high velocity, into the receiving-chamber T, to be delivered therefrom into the room containing the stove, or carried upwards, and discharged into the rooms above, or the heated air may be distributed to different rooms.

These advantages are attained without any extraneous flues or air-passages, and in a comparatively-contracted stove, and in a great measure depend upon the arrangement and disposal of the peculiar crescent-shaped air-chambers.

A serious objection to coal-reservoirs has been the burning away of the lower ends, which are exposed directly to the action of the fire. To obviate this evil, we form on the lower end of the reservoir S the perforated air-chamber h, which performs the twofold duty of protecting the lower end of the reservoir against the action of the fire, and of permitting jets of air to pass on to the ignited fuel, and insure its more perfect combustion.

Another objection to the use of coal-reservoirs in stoves has been the escape of gases, generated in the fuel, into the room where the stove is situated. To prevent this, we use the lid or cover W in the feeder U; not an ordinary cast-iron plate, resting on ledges, but a cover, turned, planed, or otherwise made perfectly true, and resting on ledges prepared in a similar manner, so that a perfectly-tight joint is insured, and the escape of gas thereby prevented.

Although we have frequently referred in the above description to certain crescent-shaped chambers, it will be readily understood that the precise form shown need not be adhered to in all cases, as the shape may be considerably modified without departing from the main peculiarities of our invention.

We claim as our invention, and desire to secure by Letters Patent—

1. The chamber F, between the fire-pot and casing G, when the said chamber has, in front, openings for the admission of cold air, and communicates at the rear with openings for the passage of another current of cold air, all substantially as and for the purpose herein set forth.

2. We claim the above in combination with the air-chamber K at the rear of the fire-chamber.

3. The plates J and H, between which is a passage, forming a communication between the lower crescent-shaped chamber K and upper chamber Q, as described.

4. The air-opening q, communicating with the space between the plates J and H, as set forth.

5. The crescent-shaped air-chamber Q, open in front for the passage of the products of combustion from within the space enclosed by the inner casing of the said chamber round to the rear of the same, as set forth.

6. Openings for admitting cold air at three different points to the within-described chambers or their

equivalents, in which the air is heated, and by which the heated air is delivered in one volume to a receiving chamber, T.

7. The coal-reservoir S, suspended within but at a distance from the chamber Q, as set forth.

In testimony whereof, we have signed our names to this specification in the presence of two subscribing witnesses.

DAVID STUART,
LEWIS BRIDGE.
